UNITED STATES PATENT OFFICE.

BYRON B. GOLDSMITH, OF NEW YORK, N. Y.

PAPER-CLIP

1,259,849.

Specification of Letters Patent. Patented Mar. 19, 1918.

Application filed August 5, 1914. Serial No. 855,136.

To all whom it may concern:

Be it known that I, BYRON B. GOLDSMITH, a citizen of the United States, residing at New York city, in the county of New York 5 and State of New York, have invented certain new and useful Improvements in Paper-Clips; and I do hereby declare the following to be a full, clear, and exact description of the invention, such as will enable others skilled in the art to which it 10 appertains to make and use the same.

The present invention has relation to improvements in spring clips for fastening papers together at their edges.

15 Many forms of clips have been proposed wherein are employed suitable lengths of wire of proper resilience and temper bent in various shapes, and so arranged as to be applied over the edge of two or more sheets 20 of paper, cardboard or the like so as to grip or compress the same firmly together. Many of these, while acting effectively for the purpose in view when once in place, are nevertheless difficult to apply to the 25 edges intended to be gripped.

It is the object of the present invention to provide an improvement applicable to practically all forms of clip of this general character, as well as to clips made of material 30 other than wire, whereby the same are made more easily and conveniently adjustable to the sheets to be fastened together.

In the accompanying drawings I have 35 illustrated my invention in connection with a number of well known clips and also as applied to a sheet metal clip: but it is to be understood that I do not limit my invention to its use in connection with these particular forms, since the same is capable of embodiment in an indefinitely large number of 40 shapes and arrangements.

In these drawings Figures 1 and 2 are 45 respectively a face and an edge view of one form of my clip, Figs. 3 and 4 are similar views of another modification, Figs. 5 and 6 are similar views of another modification, Figs. 7 and 8 are similar views of another modification, Figs. 9 and 10 are similar views of another modification, Figs. 11 and 50 12 are similar views of another modification, Figs. 13 and 14 are similar views of another modification, and Figs. 15 and 16 are similar views of another modification.

The invention resides in employing a clip 55 shaped to produce two compression members between which the sheets are to be

gripped, one of which projects somewhat beyond the extremity of the other, and producing in the longer member a small return bend concave toward the shorter member 60 and preferably partly overlapped by the extremity of the latter. Into this bend, and under the extremity of the shorter member of the 65 p. the edge of the united sh. may be easily and conveniently pressed, as to lead such edge instantly and without any trouble into position easily to cause the two members to part to receive the sheets.

In Fig. 1 is shown a clip of a familiar 70 form in which a single length of resilient wire is so coiled as to form a shorter member 20 of loop form and a longer member 21 of similar form. The papers are pressed in between these two loops, and are held together by their tendency to assume a common plane. When this form of clip is made in accordance with my invention, a slight return bend 22 is formed in the longer loop 21 as clearly shown in Fig. 2. This is 75 concave toward the shorter loop 20, as shown, and affords a leading-in point to which the edges of the united sheets are applied in the manner indicated in dotted lines, the same being led by the curve directly under 80 the extremity of the shorter member. By 85 this expedient a certain and expeditious application of a clip is accomplished.

In Figs. 3 and 4 the longer member of the 90 wire clip is a U-shaped loop 23 and is provided with concave return bends 22. The shorter member is duplicated in the extremities of the wire which are bent back substantially parallel with the sides of the U and are carried down far enough to bring 95 their extremities about opposite the bends 22.

In Figs. 5 and 6, the two loops of Figs. 1 and 2 are given a triangular form, and the longer of the two has the intaking or inleading bend 22. 100

Figs. 7 and 8 show a clip formed of a length of wire formed in a wide U shape, the ends being curved in toward each other and led down parallel to form the longer resilient member. The lower extremities 105 are preferably again curved upward at 24 toward the U-shaped shorter member, and the entire longer member is given a return bend 22 for the purpose described.

In Figs. 9 and 10 the shorter member is a 110 triangular loop and the longer member is formed by a single end carried down behind

the middle of the loop and provided with the inleading bend 22 as before.

In Figs. 11 and 12 the shorter member shown in Fig. 9 is modified in form and the 5 end of the wire which is not carried down is made to weave under and over the other parts of the wire, as shown at 25.

Figs. 13 and 14 show a form somewhat like that shown in Figs. 3 and 4, but here 10 the return bends at the ends of the wire, forming together the shorter member, are more greatly extended, and are given two square turns 26, 27, as shown.

In Figs. 15 and 16 is shown a clip formed 15 of a piece of resilient sheet metal, wherein the flap 28 forms the shorter member, and the more extended flap 29 is given the in-leading curve 22.

What I claim is—

20 In a clip for uniting sheets of paper and the like, a single piece of flexible resili-

ent metal bent upon itself to form two members, one longer than the other, and so nearly in one plane as to be adapted to be spread apart by the edges of the paper when 25 applied thereto, the longer of said members lying parallel to the shorter member from their junction to a point just behind the extremity of the shorter member and being there bent to form a return curve concave 30 toward the extremity of said shorter member and out of contact therewith, the tip of said longer member being continued beyond said curve in substantially the original plane of said longer member. 35

In testimony whereof, I have affixed my signature, in presence of two witnesses.

BYRON B. GOLDSMITH.
